UNITED STATES PATENT OFFICE.

BIRGER BARK, OF CHICAGO, ILLINOIS, ASSIGNOR TO SHERMAN S. JEWETT & CO., OF BUFFALO, NEW YORK.

DESIGN FOR A SHELF-BRACKET OR WALL-PIECE.

SPECIFICATION forming part of Design No. 21,305, dated January 19, 1892.

Application filed October 24, 1891. Serial No. 409,723. Term of patent 7 years.

To all whom it may concern:

Be it known that I, BIRGER BARK, a citizen of the United States, residing at Chicago, in the county of Cook and State of Illinois, have 5 invented and produced a new and original Design for Stove-Shelf Brackets and Wall-Pieces, of which the following is a specification.

My design is for the ornamentation of the 10 backing or wall-piece used in connection with the high or flue shelf of a cooking stove or range.

The drawing shows in perspective a view 15 of my design in connection with a cooking stove or range D, the flue A, and the high shelf B.

The design, as a whole, consists in the wall-piece proper, designated by the numerals 1, 2, and 3, and the flue-piece, designated by the 20 numerals 4 and 5. Below the shelf the wall-piece is provided with the arabesque ornamentations 11, arranged on either side of the flue A. The parts 1 of this portion of the design are alike and balance each other. The

two parts 2 2 of the wall-piece, which are 25 arranged above the shelf B, are also of arabesque ornamentation, and, as shown, join with the portions 1 of the design at 6 beyond the ends of the shelf. Between the upper portions the two parts 2 2 of the design and connecting them are the leaf ornaments 3. Surrounding the damper C in the flue is the flue-piece, which is in general outline of circular form. It consists of two spreading or fan-like portions 4 4, arranged one above and the 30 other below the damper, while between these fan-like ornaments are arranged the curved ornaments 5 5, concentric with the damper. 35

What I claim is—

The design for the backing for the flue or 40 high shelf of a stove, substantially as herein described and shown.

In testimony whereof I affix my signature in presence of two witnesses.

BIRGER BARK.
